SELECTIVE DROP END DOOR BALANCER

BACKGROUND OF THE INVENTION

Railway gondola cars having drop end doors that are hinged at the bottom and in opening swing inwardly to a substantially horizontal position along the floor, often have each door equipped with a door balancer providing a spring force for assisting in closing and cushioning opening. Heretofore, such doors at maximum have been about 3 feet high and 600 pounds in weight and for such a door a balancer of the type disclosed in Goodwin U.S. Pat. No. 2,580,760, issued Jan. 1, 1952, is entirely practical. However, to meet the demands of railroads and shippers for freight cars of increased capacity, gondola cars have now been designed with oversize drop end doors as high as 6 feet and weighing as much as 1,450 pounds. A conventional door balancer may have one or more springs, usually rods or coils in torsion, and, invariably, each spring acts to resist opening or assist closing movement of the door over the full range between open and closed positions. Attempts to adapt such balancers to oversize doors by increasing their spring force have not been successful, the difficulty, it has now been determined, being the too great variation between the straight line force plot or curve of the torsion springs and the sine load curve of the oversize door in swinging between closed and open positions.

SUMMARY OF THE INVENTION

The improved door balancer of the present invention provides an effective load balance for even oversize doors by using full range main and part range compensating springs which cooperate to hold within acceptable limits the force required at any point in closing the door. In its preferred form the improved balancer uses torsion springs and enables the forces exerted by each and the relative ranges of their actions to be selected to suit end doors of any given size. The preferred balancer also is installable as a unit with the door, has its springs enclosed to protect them against the elements and during assembly is adjustable to compensate for manufacturing or assembly tolerances or other special requirements of a particular installation.

With the foregoing its principal objectives, other objects and advantages of the invention will appear hereinafter in the detailed description, be particularly pointed out in the appended claims, and be illustrated in the accompanying drawings, in which:

FIGURE DESCRIPTION

FIG. 1 is a fragmentary rear elevational view of a drop end door and associated structure of a railway gondola car showing a preferred embodiment of the balancer of the present invention applied to the door;

FIG. 2 is a fragmentary central vertical sectional view on an enlarged scale of the structure of FIG. 1, taken along lines 2-2 of FIG. 3.

FIGS. 3, 4 and 5 are fragmentary vertical sectional views on the same enlarged scale taken along lines 3-3, 4-4 and 5-5, respectively, of FIG. 1;

FIG. 6 is a fragmentary horizontal sectional view taken along lines 6-6 of FIG. 4; and

FIG. 7 is a graph showing the relation between the load curve of a typical oversize door and the torque curve of a balancer of this invention.

DETAILED DESCRIPTION

Referring now in detail to the drawings in which like referenced characters designate like parts, the improved gondola car end door balancer of the present invention, while applicable to end doors of smaller size, is particularly designed for the recently proposed oversize doors. In either case, the door, designated as 1, will be one of a pair at opposite ends of the body, indicated at 2, of the gondola car (not otherwise shown).

As customary, the illustrated door 1 is mounted on and between the adjoining corner posts 3 at the corners of the body 2 at its end of the car for pivoting, hinging or swinging about a horizontal axis extending laterally of the body adjacent the door's bottom 4 and swings or moves from a vertical position in which it is stopped by engagement of its front or front faces 5 with instanding flanges 6 on the corner posts, to a substantially horizontal position in which it lies along the body's floor 8.

As does the balancer of the Goodwin patent, the improved balancer 9 itself preferably provides the pivotal mounting by including a pair of laterally spaced body brackets 10 at opposite sides of the door, each of which is fixed, as by riveting, to and instands laterally from one of the corner posts 3. The body brackets 10 are laterally aligned and each pivotally mounts one of a pair of laterally spaced and aligned door brackets 11 fixed or secured to or rigid with and at opposite sides of the door 1. In the preferred pivotal mounting each door bracket 11 has a tubular part 12 forming a bottom or lower corner of the door and a plate part 13 which is fixed to or rigid with the tubular part and through which the bracket is riveted or otherwise fixed to or made rigid with the overlying body portion 14 of the door. The tubular part 12 of each door bracket 11 has in an outer end portion 15 a cylindrical aperture or opening 16 in which is journaled or rotatably received or seated a correspondingly cylindrical hollow trunnion or boss 17 on and integral or rigid with and instanding from the adjoining body bracket 10. Concentric or coaxial, the bosses 17 and tubular parts 12 of the body and door brackets together provide a bottom hinge for the door and fix the laterally extending, horizontal axis on which the door swings or moves between closed and open positions.

In addition to being the door butts or parts of the hinge on which the door 1 swings, the door brackets 11 in the preferred embodiment also are the opposite end sections of a spring housing 18, extending laterally across the bottom 4 of the door. If, as disclosed, the center section 19 of the housing 18 between and connecting the tubular parts 12 of the door brackets 11, is a pipe or tube section of appropriate length and diameter, fixed or secured as by welding to the overlying body portion 14 of the door, the tubular parts may have on their inner end portions 20 instanding annular or cylindrical flanges 21 telescoped into or received in the outer ends of the center section.

The improved balancer 9 depends for assisting an operator in lifting the door 1 to closed position upon a main or primary spring or spring group 22 and one or more compensating, secondary or auxiliary springs or spring units 23. At least the main and preferably all of the plurality of springs are torsion springs. The main spring or group 22 is intended to act over the full range of movement of the door, while the purpose of the compensating spring or springs 23 is to compensate for the differences between the straight line torque plot or curve of the main spring 22 and the sine load, force or torque curve of the door, so as to reduce the effort or force required to be exerted by an operator at any point in closing the door, with the reduction preferably sufficient to enable the door to be closed by a single operator. The preferred main spring 22 is a plural or, for an oversize door, multiplate torsion bar which is anchored at opposite ends or other spaced points to the body 2 and the door 1 and acts throughout the movement of the door between closed and open positions, storing energy or being energized as the door is opened and, on subsequent closing, restoring or releasing that energy or torsional force to assist the operator.

Conveniently housed or contained in and extending longitudinally of the housing 18 substantially on or along the door's hinging axis, the torsion bar 22 may extend through the housing with one end suitably anchored to the car body and the other to the door, as do the torsion bars in the equalizer of Ingram U.S. Pat. No. 2,567,287, issued Sept. 11, 1951, but preferably follows the Goodwin patent in being divided substantially at the longitudinal center of the housing into two

half springs 24. Each of the preferred half springs extends through its half of the center pipe section 19, the tubular part 12 of the adjoining door bracket 11 and the hollow trunnion 17 of the cooperating or adjoining body bracket 10 and has its outer end anchored in a fixed anchor 25 in the body bracket in the form of a generally rectangular slot in that bracket at the outer end of and centered radially on the trunnion. The opposite or inner ends of the half springs 24 are received or anchored in opposed or oppositely facing, generally rectangular seats or slots 26 in a center or door anchor or anchor member 27. Initially rotatably mounted in the center section 19 of the housing 18, the anchor member 27 has a radial leg 28 extending through an initially open radial slot 29 in the housing for enabling the member to be rotated during assembly to adjust or set the torsion of the main spring 22 in the closed position of the door at whatever value is desired. The anchor member is then welded in place or otherwise fixed to the door to hold or maintain this value when the door is closed and as the door or moving anchor apply to or receive from the main torsion spring 22 a torsional or twisting force over the range of movement of the door between closed and open positions.

The force or torque required in the absence of a spring assist for lifting the door 1 through approximately 90° from its substantially horizontal open position to its vertical closed position, will progressively decrease from a maximum at open position to zero at closed position, with the maximum determined by the weight and height of the door. As mentioned earlier, this progressive decrease follows a sine curve, while the energy or torque output of an energized or torsioned torsion spring decreases at a fixed rate and therefore follows a straight line. Consequently, any arrangement of torsion springs, in which all act in the usual way throughout the range of movement of the door between open and closed positions, can match in its available torque the force or torque required to lift the door at most at only two points and elsewhere in the range of movement the available and required torque will differ to a greater or lesser degree. It is this variance between the lifting force required on the door and the force derivable from one or more torsion springs so acting over the range of movement of the door from open to closed position, that disables such springs from effectively assisting in closing an oversize drop end door. However, the energy derivable from a plurality of torsion springs can be an effective assist in closing even an oversize door if, in accordance with this invention, one or more act over the full range of movement of the door, while another or others, by acting over a lesser range, compensate at least partly for the differences within that range between the required force and the force derivable from the full range spring or springs.

With the main torsion spring or bar 22 the full range spring, the preferred balancer has as its part or partial range compensating spring 23 one or a pair of coil springs acting in torsion and encircling the main spring and substantially centered therewith on the door's hinge axis. Each such compensating spring suitably is housed in the tubular part 12 of one of the door brackets 11 with an inner end 30 in the inner end portion 20 of that part and lockable or holdable against and limited in movement relative thereto in an uncoiling or energy releasing direction by a radially instanding stop or shoulder 31 on that portion. The opposite or outer end 32 of the coil spring 23 is received in the outer end portion 15 of its door bracket and engageable for limiting its turning or movement relative to the end portion in an uncoiling or torque-releasing direction by a radially instanding stop, stop lug, shoulder or abutment in that end portion and facing oppositely from the radially instanding limit stop or stop shoulder 31 in the inner end portion 20. The spring's outer end 32 is so bent or formed as to lie or be disposed in the path of rotary movement relative to the door bracket 11 of a body or power lug 34 fixed to or rigid with and radially outstanding from the boss 34 on the adjoining body bracket 10. While both the door stop lug 33 and the body lug 34 project or extend radially into the annular space 35

between the boss 17 and the side wall 36 of the outer end portion 15 and from opposite directions, the body lug is positioned radially inwardly of the door lug so that the lugs are clear or free to pass each other. On the other hand, both of these lugs, by extending into the portion of the space 35 occupied by the outer end 32 of the compensating spring 23, are disposed in the path of and engageable with that end when presented thereto. Contained after assembly within or inside the tubular part 12 of the related door bracket 11, the body lug 34 is insertable thereinto by appropriate radial slotting of the end wall 37 of the outer portion 15 about the trunnion-receiving aperture 16.

When the balancer is operating in service, the outer and inner end portions 15 and 20 of the tubular part 12 of each door bracket 11 are fixed to the door for turning or swinging therewith relative to the adjoining body bracket 10. However, whether so fixed by welding or other suitable means, the end portions 15 and 20, if the bracket is to house a compensating spring 23, initially are rotatable relative to the part's center or midportion 38, which, in addition to being interposed between and axially spacing the end portions, is integral or rigid with the plate part 13 of the door bracket 11 through which the latter is fixed to the body portion 14 of the door. It is this initial relative rotatability of the end portions that is employed to pre- or selectively set the torque or torsion of the compensating spring 23, as well as to predetermine or selectively set the partial interval or range within the full range of movement of the door between closed and open positions over which the compensating spring is active.

Turning of the end portions 15 and 20 oppositely in the coiling direction of the coil spring 23 to the point at which each of the stops 31 and 33 just engages the related of the ends 30 and 32 of the spring will leave the spring free, but by further opposite turning of the end portions in the same direction the spring can be torsioned or energized to any desired extent. This torsioning alone affects nothing but the spring when the end portions are locked in place since they are both on and part of the door 1. However, if, after their relative rotation to apply a predetermined or selected normal or initial torsion or torque to the spring and with the door in its vertical closed position, the end portions 15 and 20 are turned or rotated in unison relative to the adjoining body bracket 10 to a point at which the stop lug 33 on the outer end portion is in advance in a door opening direction of the power lug 34 on the body boss 17, the arc or angle between or relative angularity of the lugs will be that of the lost motion or delay through which the door can swing in opening without bringing the compensating spring into action. Consequently, by rotating the end portions 15 and 20 relative to each other and the adjoining boss 17 before welding or otherwise fixing those sections to the center section 38 of the door bracket, it is possible to preset or predetermine both the initial or normal torsion or torque of the compensating spring 23 and the partial range within the full range of movement of the door over which the spring acts or is operative. If, instead of a single compensating spring 23, two are employed, one in the door bracket part 12 at each end of the housing 18, the individual adjustment derivable from the initial rotatability of the end portions 15 and 20 of the two door brackets enables the preset torsions of the springs and the partial ranges over which they act to be the same or different, as desired.

The effect of compensating springing in reducing over the range of movement of the door the difference at critical points between the torque required for equilibrium with the load of the door and that obtainable from springing acting over the full range of movement of the door, is exemplified in the graph of FIG. 7. In that graph, the sine curve of the door load or torque required for equilibrium at any point in the range of movement of a 6 feet, 1,450 pound drop end door, has been plotted against the composite stepped torque curve produced by a full range main torsion spring without preset and a pair of pretorsioned compensating springs preset to act over different ranges.

Whether or not any of the main and compensating springs 22 and 23 is pretensioned, each will be energized over its range of action as the door is opened and release its stored energy over the same range in a closing operation. As in the graph of FIG. 7, the force of gravity on the door, once it is moved from its vertical closed position, may suffice alone to energize the springs, although it is entirely possible that in some installations it may be found desirable to supplement the force of gravity by a force applied by the operator at some points during opening in order to decrease the maximum effort required to be exerted by him in closing the door. In any case, the springs will assist closing and, in being energized during and consequently resisting opening of the door, will cushion opening.

From the above detailed description it will be apparent that there has been provided an improved balancer for drop end doors of railway gondola cars, which, by using both full range main and part range compensating springs, effectively assists closing of even an oversize door and is adjustable during assembly for selective action of its one or more compensating springs to suit particular installations. It should be understood that the described and disclosed embodiment is merely exemplary of the invention and that all modifications are intended to be included that do not depart from the spirit of the invention and the appended claims.

I claim:

1. A door balancer for a drop end door hinged between sides of a body of a railway gondola car for movement between a vertical closed position and a substantially horizontal open position, comprising main torsion spring means acting between the door and the body over the full range of movement of the door between closed and open positions, compensating spring means acting between the door and the body, and means for limiting the action of said compensating spring means to a part of said full range.

2. A door balancer according to claim 1, wherein the compensating spring means are torsion spring means.

3. A door balancer according to claim 2, wherein the main and compensating spring means resist and are energized in opening and release energy and assist in closing of the door.

4. A door balancer according to claim 3, wherein the main spring means is a torsion bar, the compensating spring means

are coil spring means in torsion, and the main and compensating spring means extend along and are substantially centered on the hinging axis of the door.

5. A door balancer according to claim 3, wherein the limiting means is selectively adjustable prior to service operation for varying the partial range of action of any of the compensating spring means.

6. A door balancer according to claim 3, wherein the limiting means is selectively adjustable prior to service operation for varying both the partial range of action and the normal torsion of any of the compensating spring means.

7. A door balancer according to claim 4, wherein the torsion bar extends through and the compensating spring means are contained in a housing fixed to and extending across the bottom of the door.

8. A door balancer according to claim 7, wherein the door is hinged to the car body by a pair of door brackets rigid with and at lower corners of the door and each having a part journaling a trunnion rigid with and instanding laterally from a body bracket fixed to an adjoining side of the body, said door bracket parts form end sections of the housing, and at least one of said parts houses a compensating coil spring.

9. A door balancer according to claim 8, wherein the part of each door bracket housing a compensating coil spring includes initially relatively rotatable outer and inner end portions each receiving a corresponding end of the coil spring, and stop means in said end portions and each limiting turning of the spring end therein in an uncoiling direction relative thereto for enabling the torsion of the spring to be selectively preset by relative rotation of said end portions prior to fixing thereof to the door bracket.

10. A door balancer according to claim 9, including for each door bracket part housing a compensating coil spring a radially outstanding lug on the trunnion journaled in the outer end portion of the part, said lug being disposed radially inwardly of the stop means and in the path of the spring end in said outer end portion for energizing and receiving energy from the spring respectively on opening and closing of the door over a range predetermined by the relative angular dispositions in which the lug and stop means are selectively set in the closed position of the door.
